United States Patent Office

Des. 209,381
Patented Nov. 21, 1967

209,381

AX

Aldor S. E. Reuterfors, Rockford, Ill., assignor to
Ewing Manufacturing Company, Inc., Rockford,
Ill., a corporation of Illinois

Filed Nov. 4, 1966, Ser. No. 4,556

Term of patent 14 years

(Cl. D93—4)

FIGURE 1 is a perspective view of an ax embodying my new design;

FIG. 2 is a side elevational view thereof, the other side being a mirror image thereof;

FIG. 3 is a bottom elevational view thereof;

FIG. 4 is an end view thereof as seen from the left of FIG. 2; and

FIG. 5 is a cross-sectional view taken substantially along line 5—5 in FIG. 2.

I claim:

The ornamental design for an ax, substantially as shown and described.
